[57] **CLAIM**

The ornamental design for a bracket for garment hangers or the like, as shown.

DESCRIPTION

FIG. 1 is a side elevational view of a bracket for garment hangers or the like showing my new design; FIG. 2 is a top plan view thereof;

FIG. 3 is a bottom plan view thereof;

FIG. 4 is an enlarged front elevational view thereof;

FIG. 5 is an enlarged rear elevational view thereof; and

FIG. 6 is an enlarged fragmentary perspective view thereof.
